US00D493828S1

(12) United States Design Patent (10) Patent No.: US D493,828 S
Edwards (45) Date of Patent: * Aug. 3, 2004

(54) INFORMATION CARD

(75) Inventor: Paul Edwards, Orsett (GB)
(73) Assignee: Quadroprint Limited, London (GB)
() Term: 14 Years
(21) Appl. No.: 29/164,899
(22) Filed: Jul. 31, 2002

(30) Foreign Application Priority Data

Feb. 1, 2002 (GB) 3001194
(51) LOC (7) Cl. 19-01
(52) U.S. Cl. D19/1
(58) Field of Search D14/435, 436,
D14/437, 438; D19/1, 2, 9, 10, 11, 12,
32, 33, 34; D20/11, 40; 40/1, 124.01, 360;
235/380, 435, 487, 488; 283/34, 35, 36,
37, 38, 39, 40, 41, 42, 43; 360/2
